UNITED STATES PATENT OFFICE.

JOHN H. FONES, OF OAKLAND, CALIFORNIA.

WRENCH.

Application filed April 26, 1922. Serial No. 553,640.

To all whom it may concern:

Be it known that I, JOHN H. FONES, a citizen of the United States, residing at Oakland, in the county of Alameda and State of California, have invented new and useful Improvements in Wrenches, of which the following is a specification.

This invention relates to improvements in wrenches of the type described in Letters Patent of the U. S. numbered 1,362,687, issued to me on the 21st of December, 1920, and has for its primary object to provide an improved simplified wrench construction wherein the number of parts is reduced to the minimum, the expense of manufacture is materially lessened and the operation as to adjustment of the jaws may be more quickly and easily effected.

An object of the invention is to provide in a wrench of the character described an improved jaw adjusting locking mechanism which consists of but few and simply constructed parts or elements capable of being readily assembled or disassembled and which may be readily and easily operated to provide for adjustment and locking of the jaws.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Fig. 1 represents a side elevation of a wrench constructed in accordance with the present invention.

Fig. 2 represents a fragmentary sectional view through the adjustable jaw partly illustrating the adjusting and locking means therefor.

Fig. 3 is a rear elevation of the adjustable jaw.

Fig. 4 is a sectional view taken on line 4-4 of Fig. 2, the adjustable jaw being omitted.

Fig. 5 is a sectional view taken on line 5-5 of Fig. 2.

Referring specifically to the drawing wherein I have illustrated one practical modification of the invention, 1 indicates a fixed jaw carried on the outer end of a handle 2, upon which handle an adjustable jaw 3 slides so as to cooperate with the fixed jaw 1. The adjustable jaw 3 is provided with a recess 4 on the under side of its body whereby access may be had to a rack 5 formed on the lower edge of the handle 2.

Mounted for rotation within the recess 4 and for bodily movement towards and away from the rack 5, is a worm element 6, which when engaged with the rack 5 will provide for adjustment and for locking of the adjustable jaw and when disengaged from the rack will permit of a quick movement or adjustment of the jaw towards or away from the fixed jaw.

A particular feature of the invention is the mounting of the worm element 6, the said mounting principally comprising a pin or shaft 7 upon a mediate portion of which the worm element 6 is fixed by means of a transversely inserted screw or pin 8. The body portion of the jaw 3 is formed with a longitudinally extending cylindrical bore 9 for the pin 7, there being a portion of said bore on each side of the recess 4 whereby end portions of the pin may be mounted for movement in said bore. The pin 7 instead of being cylindrical in cross section, is formed, more particularly where it extends from the opposite ends of the worm element 6, so as to be more or less semi-cylindrical and so that there will be provided longitudinally extending ribs 10 on said pin. The outer edges of these ribs are adapted to have a working fit with the bore so that the pin will properly rotate when the member 6 is turned. Extending longitudinally of the bore and opening into the latter, are grooves 11 being of just sufficient width to accommodate the ribs 10. The formation of the ribs and grooves is such that the pin may be turned a considerable extent before bringing the ribs into registration with the groove and in this way provision is made for adjustment of the movable jaw by turning the worm element when the latter is engaged with the rack 5.

When it is desired to effect quick adjustment or movement of the movable jaw, the worm element 6 is turned so that the ribs 10 on the pin 7 will be brought into registration with the grooves 11. By then pulling

outwardly on the worm element, said element and the pin will be moved due to the extension of the ribs 10 into the grooves and the worm will be brought clear of the rack whereupon the jaw 3 may be moved as desired relative to the jaw 1. After adjustment of the jaw 3 in this manner the worm may be pushed inwardly into engagement with the rack and given a slight turn so as to move the ribs 10 out of registration with the grooves 11 whereupon the worm 6 will be locked with the rack and the jaw 3 will be held in adjusted position.

One end of the pin 7 terminates short of the adjacent end of the bore 9 and has engaged therewith a circular disc 12, which disc is yieldingly held against said end by a helical expansion spring 13 mounted within the bore. The spring 13 places the pin 7 under tension such that when the worm 6 and pin are moved and the worm is free of the rack, its position will be maintained due to such pressure. The disc 12 provides for smooth and frictionless transmission of pressure to the pin which due to its irregular shape at its ends, would otherwise become entangled with the end of the spring.

With the adjusting and locking mechanism of this invention it will be seen that the wrench may be very easily constructed and readily and easily assembled and disassembled since but few parts are required to provide the said mechanism. The mechanism is protected and concealed for the most part such that it will not be subject to rust or damage due to exposure to the elements.

I claim:

1. A wrench comprising a handle having a rack and a jaw thereon, a second jaw slideable upon the handle and having a recess therein permitting access to the rack, said movable jaw having a bore therein, a pin movable bodily within the bore, a rib on said pin, said jaw having a groove opening into the bore and adapted to receive said rib to permit movement of the pin towards and away from the rack and a worm on the pin and adapted to be moved into and out of engagement with the rack and rotated while in contact with the rack.
2. A wrench comprising a handle having a rack and a jaw thereon, a jaw slideable upon the handle and provided with a recess permitting access to the rack and with a pin

bore opening into the recess, a pin rotatable within the bore and extending into the recess, a worm fixed to the pin and adapted to engage the rack and means providing for movement of said pin and worm whereby the worm may be disengaged from the rack which means comprises a rib extending longitudinally on the pin and a complementary longitudinal groove in the bore adapted to receive said rib.

3. A wrench comprising a handle having a rack and a jaw thereon, a jaw slideable upon the handle and provided with a recess permitting access to the rack and with a pin bore opening into the recess, a pin rotatable within the bore and extending across the recess, a worm fixed to the pin and adapted to engage the rack, means providing for movement of said pin and worm whereby the worm may be disengaged from the rack which means comprises a rib extending longitudinally on the pin and a complementary longitudinal groove in the bore adapted to receive said rib and spring means yieldingly engaging one end of the pin within the bore.

4. A wrench comprising a handle having a rack and a jaw, a second jaw slideable upon said handle and having a recess permitting access to the rack, a worm in said recess adapted to cooperate with the rack, and a pin extending into said second jaw and worm parallel to the rack for mounting the worm in said recess, said pin and one of the parts into which it extends being capable of relative lateral movement and having a rib on the pin and a groove in the said part to limit lateral movement to the position of registration of said rib and groove in the rotation of the worm.

5. A wrench comprising a handle having a rack and a jaw, a second jaw slideable upon the handle and having a recess permitting access to the rack, a worm in said recess adapted to cooperate with the rack, and a pin projecting from said worm into said second jaw parallel to the rack for mounting the worm in the recess, said pin being capable of lateral movement in the second jaw and the pin and second jaw having one a rib and the other a groove to limit said lateral movement to the position of registration of said rib and groove in the rotation of the worm.

JOHN H. FONES.
